UNITED STATES PATENT OFFICE

EDWIN B. LANGSDORF, OF NEW YORK, N. Y.

DESIGN FOR A MIRROR OR SIMILAR ARTICLE

Application filed January 29, 1930. Serial No. 34,333. Term of patent 3½ years.

To all whom it may concern:

Be it known that I, EDWIN B. LANGSDORF, a citizen of the United States, and a resident of the city of New York, borough of Manhattan, in the county and State of New York, have invented the new, original, and ornamental Design for Mirror or Similar Article, of which the following is a specification.

Reference is had to the accompanying drawing, forming part thereof, wherein

I claim:—

The ornamental design for a mirror or similar article substantially as shown.

EDWIN B. LANGSDORF.
